UNITED STATES PATENT OFFICE.

LOYD J. CALDWELL, OF WILSON, IDAHO.

WATER-BALANCED ELEVATOR.

1,216,546.

Specification of Letters Patent.

Patented Feb. 20, 1917.

Application filed June 1, 1916. Serial No. 101,135.

To all whom it may concern:

Be it known that I, LOYD J. CALDWELL, a citizen of the United States, residing at Wilson, in the county of Owyhee, State of Idaho, have invented certain new and useful Improvements in Water-Balanced Elevators; and I do hereby declare the following to be a full, clear, and exact description of the invention, such as will enable others skilled in the art to which it appertains to make and use the same.

This invention relates to elevators and has special reference to an elevator counterbalanced by a water containing tank, the latter being arranged to contain more or less water according to the weight to be counterbalanced and the direction of movement desired for the elevator car.

One important object of the invention is to provide an improved and simplified elevator arrangement wherein the car will be moved by water carried in a suitable tank and acting as a counterbalance, the car and tank being connected and supported by a supporting cable and moving in one direction or the other in accordance with the quantity of water in the tank.

A second important object of the invention is to provide an improved means for filling and emptying the tank.

A third important object of the invention is to provide a novel clamp brake arrangement for use in connection with a car of this description, the brake being so arranged as to clamp the supporting cable with the car in any desired position.

A fourth important object of the invention is to provide a controlling device for the water valves of such an elevator which will pass through the car and at the same time be within reach of a person standing at the shaft door at each floor so that such person may operate the car to bring the same opposite the door without the services of a regular and constant attendant being necessitated.

A still further important object of the invention is the provision of a stationary cable passing through the car and so arranged that a person on the car may cause the latter to move up and down in the elevator shaft at will, when the car is properly counterbalanced.

With the above and other objects in view, as will be hereinafter apparent the invention consists in general of certain novel de-

tails of construction and combinations of parts hereinafter fully described, illustrated in the accompanying drawings, and specifically claimed.

In the accompanying drawings, like characters of reference indicate like parts in the several views, and:

Fig. 1 is a section through an elevator shaft showing several of the floors of a building and the improved arrangement of elevator disposed in the shaft.

Fig. 2 is a similar section but taken at right angles to Fig. 1;

Fig. 3 is a plan view of the floor of the elevator cage;

Fig. 4 is an enlarged detail view of the cable clamp;

Fig. 5 is a perspective of the rod grip;

Fig. 6 is a detail view of a modified form of brake, the same being applied to the sheave over the elevator cage.

In the form of the invention illustrated in Figs. 1 to 5 there is disclosed an elevator cage or car 10 which moves up and down a shaft 11 between guides 12. On the floor of the car is provided a foot brake 13 which is so arranged as to engage one of the guides when thrust upon by the foot so that the car may be checked in its motion thereby, this foot brake being of any preferred construction which I may see fit to use.

Attached to the top of this car is a cable 14 which is trained over a sheave 15 suitably mounted on the frame-work of the elevator shaft. The cable then extends laterally and is trained over a second sheave 16 similarly supported in the shaft and then extends downward to a counterbalance tank 17. Mounted at the top of the elevator shaft is a supply tank 18 and at the bottom of said shaft is a receiving tank 19. Extending from the tank 18 is a pipe 20 and to the end of this pipe is connected a flexible tube or hose 21 which is in turn connected to the top of the tank 17. In the pipe 20 is a valve 22 which is controlled by an operating handle 23.

Leading downward from the tank 17 is a hose 24 which is connected to a pipe 25 communicating with the tank 19. In the pipe 25 is a valve 26 provided with an operating handle 27 and the two valves 22 and 26 are in vertical alinement. The operating handles 23 and 27 are connected by a rod 28 which passes vertically through the car 10, as shown. Moreover these valves 22 and 26

are so arranged that when one of the valves is opened the other will be closed and this opening and closing of the valves is effected by vertical movement of the rod 28 in one direction or the other as can be readily understood. By means of this apparatus the car may be caused to move in either direction since it will only be necessary to put a sufficient quantity of water in the tank 17 by opening the valve 22 to counterbalance the weight of the car 10 and thus cause the car to move upward; or if it is desired to move the car downward, water is let out of the tank 17 by opening the valve 26 whereupon the car will descend. In each of these instances, if the counterbalancing has been properly performed pressure on the foot brake 13 will lock the car in any desired position. It is to be noted that the position of the rod 28 is such that it is close to the doors of the elevator shaft so that such rod can be operated by a person standing at one of the landings.

In order to further effect braking there is provided a clamp consisting of a base member 28' and a coacting top or cover 29, the two being held together by parallel links 30 so that movement of the cover 29 in either direction will cause the same to approach the base 28'. On this top member 29 is a lug 31 whereto is connected a rod 32 which is in turn connected to a lever 33 so arranged that its end lies adjacent the elevator shaft wall and above the doors. Connected to this end of the lever 33 is a rod 34 which passes downward through the elevator and is received in a suitable guide 35 at the bottom of the shaft. It will be obvious that movement in either direction of the rod 34 will cause movement of the lever 33 and this in turn will actuate the rod 32 to move the clamp top member 29 toward the base 28'.

In order to effect movement of this rod 34 by the car itself it is preferred to provide a mechanism to clamp the rod and car together. To this end there is provided on the floor of the car a stationary clamping member 36 and a movable clamping member 37. These two clamp members are so arranged that the rod 34 passes between them and in alignment with the path of movement of the member 37 there is a support 38 whereto is connected one of the members of a knuckle joint 39, the remaining knuckle being connected to the member 37. This knuckle joint carries a foot pedal 40 so as to be readily operated by pressure of the foot of a person riding in the elevator. In the operation of this part of the device when the pedal 40 is depressed the rod 34 will be clamped to the car and any movement of the car in one direction or the other will cause clamping movement of the cable clamp which will stop further movement of the car. Stop buttons 45' and 46'

on rods 34 and cable 41, are to be located at top and bottom of elevator shaft so as to stop car 10 before it can strike ends of shaft.

In order to more nicely and carefully control the movement of the car when the same is counterbalanced, further means are provided.

In the embodiment shown, these means consist of a cable 41 which is fixed above to the frame-work of the elevator shaft and is attached below to the upper end of a tension spring 42, the lower end of said spring being fixed to the floor of the elevator shaft. By this means, the cable is at all times kept taut. Mounted in the car is a drum 43 which is operated by a crank 44 and the cable 41 is wound around this drum. In the operation of this part of the device when the car has been just counterbalanced by the proper weight of water in the tank 17, the operator in the car may grasp the crank 44 and by rotation thereof cause upward or downward movement of the car. In this way the car can be positioned exactly at the right place so that its floor will come in alignment with the floor at which it is desired to stop.

In the modified form of brake shown in Fig. 6 there is provided on the sheave 15 a brake drum 45 surrounded by a brake band 46 which has its ends connected to a toggle 47 to which the rod 32 is attached. It will be obvious that movement of this toggle in either direction will cause clamping of the brake band on the brake drum and that such movement is effected in precisely the same manner as the movement of the member 29 toward the member 28 previously described.

The tank 18 may be supplied with water from any suitable source and in order to indicate such a source there has been here shown a valved supply pipe 48 adapted for connection to a city main or the like, although this pipe may be connected to the tank of a windmill tower or any other elevated source of water supply as desired.

There has thus been provided a simple and efficient device of the kind described and for the purpose specified.

It is obvious that many minor changes may be made in the form and construction of the invention without departing from the material principles thereof. It is not therefore desired to confine the invention to the exact form herein shown and described but it is wished to include all such as properly come within the scope claimed.

Having thus described the invention, what is claimed as new, is:

1. The combination with an elevator car; of a tank connected to the car to form a counterweight therefor, a supply pipe connected to the tank, a draw off pipe connected to the tank, vertically aligned valves in said pipes, and a rod connecting the valves and

passing through the car, a cable passing vertically through the car and having fixed ends, means within the car to cause the car to travel along the cable when said car is counterbalanced.

2. The combination with an elevator car; of a tank connected to the car to form a counterweight therefor, a supply pipe connected to the tank, a draw off pipe connected 10 to the tank, vertically aligned valves in said pipes, a rod connecting the valves and passing through the car, a cable passing vertically through the car and having fixed ends, a drum rotatably mounted in the car around 15 which said cable is wound, and a crank for the drum operable by the elevator attendant to cause travel of the car on the cable.

3. In combination, an elevator car, a counterweight therefor, a cable connecting and supporting the car and counterweight, a 20 cable grip adapted to engage said cable, a rod passing through the car and arranged to operate the grip upon movement, a gripping device fixed to the car and adapted to engage the rod to move the latter as the car 25 moves, and operating means for the rod gripping device mounted within the car.

In testimony whereof, I affix my signature, in the presence of two witnesses.

LOYD J. CALDWELL.
